US00D772929S

(12) **United States Design Patent** (10) **Patent No.:** **US D772,929 S**
(45) **Date of Patent:** **** Nov. 29, 2016**

(54) **DISPLAY SCREEN WITH ICONS**

(71) Applicant: **Vixlet LLC**, Los Angeles, CA (US)

(72) Inventors: **Juan Montes**, Los Angeles, CA (US);
Dana McMullin, Los Angeles, CA (US)

(73) Assignee: **Vixlet LLC**, Los Angeles, CA (US)

(**) Term: **15 Years**

(21) Appl. No.: **29/526,732**

(22) Filed: **May 13, 2015**

Related U.S. Application Data

(63) Continuation-in-part of application No. 29/506,179, filed on Oct. 14, 2014, which is a continuation-in-part of application No. 29/504,425, filed on Oct. 6, 2014.

(51) **LOC (10) Cl.** **14-04**

(52) **U.S. Cl.**

USPC **D14/489**; D14/488

(57) **CLAIM**

The ornamental designs for a display screen with icons, as shown and described.

DESCRIPTION

FIG. 1 is a front view of a display screen with icons showing the new design in a first embodiment; and,

FIG. 2 is a front view of a display screen with icons showing the new design in a second embodiment.

The broken lines shown in the drawings illustrate portions of the display screen with icons that form no part of the claimed design.

The icon(s) shown in this disclosure constitute a trademark of the assignee company, Vixlet, LLC. The icon(s) shown in this disclosure also constitute material covered by copyright owned by the assignee company. The assignee company, owner of the copyright and trademark, has no objection to the reproduction of the patent document or the patent disclosure, as it appears in the U.S. Patent Office records, but reserves all other copyright and trademark rights whatsoever.
